The ornamental design for a shoe midsole periphery, as shown and described.

DESCRIPTION

FIG. 1 is a perspective view of an embodiment of a shoe midsole periphery in accordance with my new design.

FIG. 2 is a right view thereof;

FIG. 3 is a left view thereof;

FIG. 4 is a front view thereof;

FIG. 5 is a rear view thereof;

FIG. 6 is a top view thereof; and,

FIG. 7 is a bottom view thereof.

Broken lines showing the remainder of the shoe in the figures are for illustrative purposes only and form no part of the claimed invention. The claimed stippled surfaces indicates contrasting surfaces of any texture, material, or color from the claimed surfaces devoid of stippling.
